US0D1062029S

(12) **United States Design Patent** (10) Patent No.: **US D1,062,029 S**
(45) Date of Patent: ** Feb. 11, 2025

(54) **LAMP CONNECTOR**

(71) Applicant: **Shenzhen Qianyan Technology LTD**,
Shenzhen (CN)

(72) Inventors: **Jinyu Pan**, Guangdong (CN); **Wenlong Wu**, Guangdong (CN)

(**) Term: **15 Years**

(21) Appl. No.: **35/517,380**

(22) Filed: **Mar. 6, 2023**

(80) **Hague Agreement Data**

Int. Filing Date: **Mar. 6, 2023**

Int. Reg. No.: **DM/229025**

Int. Reg. Date: **Mar. 6, 2023**

Int. Reg. Pub. Date: **Jun. 2, 2023**

(30) **Foreign Application Priority Data**

Sep. 8, 2022 (CN) 202230595201.6

(57) **CLAIM**

The ornamental design for a lamp connector as shown and described.

DESCRIPTION

1.1: Perspective

1.2: Perspective

1.3: Front

1.4: Back

1.5: Left

1.6: Right

1.7: Top

1.8: Bottom

1.9: Shown in environment

The dashed broken lines in reproductions 1.1-1.8 depict portions of the lamp connector that form no part of the claimed design. The dashed broken lines shown in 1.9 depict environmental structures and form no part of the claimed design.

1 Claim, 9 Drawing Sheets
